Primary Examiner — Caron D Veynar*Assistant Examiner* — Martie K Holtje(74) *Attorney, Agent, or Firm* — Schneck & Schneck;
Thomas Schneck(57) **CLAIM**

The ornamental design for a tri-loop baby carrier, as shown and described.

DESCRIPTION

FIG. 1 is a front perspective view of a tri-loop baby carrier showing my new design;

FIG. 2 is a front elevational view thereof;

FIG. 3 is a rear elevational view thereof;

FIG. 4 is a right side elevational view thereof; and,

FIG. 5 is a left side elevational view thereof.

The broken lines depicting the mother and baby in the figures have been shown for the purpose of illustrating environmental features that form no part of the claimed design.
